COMBINATION CHANGE TRAY AND MERCANDISE DISPLAY UNIT

Walter W. Reid III, Allenhurst, N. J., assignor to Charms Company, Asbury Park, N. J., a corporation of Delaware

Application October 4, 1954, Serial No. 32,532

Term of patent 3½ years

(Cl. D52—4)

Fig. 1 is a top plan view;
Fig. 2 a front elevational view;
Fig. 3 a side elevational view;
Fig. 4 a rear elevational view; and
Fig. 5 a sectional view along lines 5—5 of Fig. 1,
of a combination change tray and merchandise display
unit showing my new design.

I claim:

The ornamental design for a combination change tray
and merchandise display unit, substantially as shown.
